UNITED STATES PATENT OFFICE.

MARSHALL GARDNER, OF AURORA, ILLINOIS, ASSIGNOR TO THOMAS H. BALL
AND JAMES STONE, OF SAME PLACE, AND SIMON FLORSHEIM, OF CHICAGO,
ILLINOIS.

SEWING-MACHINE.

SPECIFICATION forming part of Letters Patent No. 402,432, dated April 30, 1889.

Application filed July 8, 1887. Serial No. 243,734. (No model.)

To all whom it may concern:

Be it known that I, MARSHALL GARDNER, of Aurora, in the county of Kane and State of Illinois, have invented certain new and useful 5 Improvements in Sewing-Machines; and I do hereby declare that the following is a full, clear, and exact description thereof, reference being had to the accompanying drawings, and to the letters of reference marked thereon, 10 which form a part of this specification.

This invention relates to an improvement in double-thread sewing-machines of that class in which the stitch is formed by reciprocating needles acting in conjunction with revolving 15 hooked shuttles.

The invention consists in the matters hereinafter described, and pointed out in the appended claim.

The device herein shown as embodying my 20 invention embraces as its main feature of novelty a revolving hooked shuttle, which is provided with peripheral teeth or recesses and is supported or sustained by means of a circular guide or race engaging the periphery 25 of the shuttle, together with a revolving drive-wheel provided with teeth or projections engaging peripheral projections or recesses upon or in the shuttle in such manner as to cause the rotation of the latter in the circular race 30 for the purpose of carrying the needle-thread loop engaged with the hook around the body of the shuttle and the thread-bobbin contained therein.

The invention is herein shown as applied 35 to a gang-machine, or one containing a plurality of needles and shuttles.

The main features of novelty of the invention may, however, be equally well applied to machines containing only a single needle 40 and a single shuttle.

In the accompanying drawings, illustrating my invention, Figure 1 is a central vertical section through the work-table and arm of a sewing-machine. Fig. 2 is an end elevation 45 of the same. Fig. 3 is a transverse vertical section of the same, taken upon line $x x$ of Fig. 1. Fig. 4 is a view showing the work-plate and parts connected therewith as viewed from beneath the machine. Fig. 5 is an en-

larged detail plan section of the several shut- 50 tles and the guides or races therefor. Fig. 6 is an enlarged detail section taken upon the oblique line $x x$ of Fig. 7. Fig. 7 is a sectional view taken through the shuttle-race upon line $x x$ of Fig. 6, showing the shuttle 55 in side view. Figs. 8, 9, and 10 are detail views of the shuttle and throat-plate of the machine, showing different positions of the shuttle. Fig. 11 is a sectional view taken through the shuttle-race upon line $x' x'$ of 60 Fig. 1, showing the side of the shuttle opposite to that seen in Fig. 7.

As illustrated in the said drawings, A is the work-plate of the machine; B, the goose-neck or overhanging frame-arm; C, the needle-bar 65 sliding vertically in the said frame-arm, and D D the needles.

E indicates the horizontal drive-shaft of the machine, which is mounted in the frame-arm B, and is provided with a crank-disk, E', from 70 which the needle-bar is actuated by means of a pitman, E''. The shaft E is provided with the usual balance-wheel, E³, and belt-pulley E⁴.

F F' indicate two metal parts or castings 75 located beneath the throat-plate A' of the machine and provided with a series of circular grooves, f f f, forming the shuttle guides or races.

G G are circular shuttles, which are fitted 80 at their edges in the grooves f f f in such manner as to be capable of freely rotating in the latter. The said shuttles contain thread-bobbins J J J.

The part or casting F is permanently af- 85 fixed to the work-plate of the machine, while the plate F', which embraces one-half of the diameter of the circular shuttle-race, is pivoted to the stationary part F F, so that the said movable part F' may be swung or moved 90 outwardly to allow of the insertion and removal of the shuttles. As herein shown, the part F' is connected by means of a pivot-pin, f', to the casting F at a point below the shuttle-guides, and is held or locked in place by 95 means of a spring-catch, F², engaging a projecting part, f², of the said casting F', in the manner clearly shown in Fig. 2.

Each of the shuttles G is made in the form of a circular ring provided at one point with an inclined notch, g , extending inwardly from its outer edge and thereby forming a hook, g' , having a pointed end adapted to engage the loop of the needle-thread as the said hook passes the needle, the said point of the hook being located in the same plane with one of the flat sides of the shuttle, as clearly shown in Fig. 5, so as to properly engage the thread-loop upon the needle, which latter passes downwardly at one side of the shuttle, in the manner clearly shown in Figs. 1, 5, and 11. The shuttle is provided about its periphery with a series of recesses or notches, g^2 g^3 g^4 , for engagement with peripheral cogs or teeth upon a revolving drive-wheel, H, located beneath the work-plate and adjacent to the several shuttles, the casting F being cut away or recessed at one side to form an opening to allow the engagement of the said drive-wheel H with the shuttles, in the manner clearly shown in Figs. 5 and 11. The said drive-wheel is shown in the drawings as mounted upon a revolving shaft, H', having bearings h h' in the casting F at either side of the said drive-wheel H and a third bearing, h^2 , attached to the machine-frame adjacent to the lower end of the frame-arm B, as clearly shown in Fig. 1.

For the general purposes of the invention any suitable actuating devices may be employed for giving rotary motion to the shaft H', so as to turn the drive-wheel and actuate the shuttles. Preferably, however, the shuttles, instead of being driven with a uniform motion, are retarded at the time the loop of the needle-thread is first engaged with the hook of the shuttle, in order that the needle 40 may have time to rise above and become free from the cloth before the needle-thread is drawn downwardly by the action of said hook, the rotation of the shuttle in the manner described being desirable for the reason that 45 the thread may be more easily drawn through the needle-hole in the cloth after the needle has been extracted therefrom.

The particular device herein shown as employed to drive the shaft H' is one heretofore 50 commonly employed, and is constructed as follows: The drive-shaft E of the machine is provided near its rear end with a crank, E⁵, which is engaged with the upper end of a lever, I, which lever is pivotally connected near 55 its middle with a horizontally-arranged connecting-bar, I', pivoted at its opposite end at i to the machine-frame. The shaft H' is provided with a crank-arm, H², having a crank-pin, h³, which is connected with the lower end 60 of the bar I by means of a connecting-rod, I². In the operation of this device the shaft H' is driven in a direction opposite to the direction of motion of the shaft E, said crank-pin h³ being pushed around by the action of the 65 short connecting-rod I² as the lower end of the bar I is rotated, in a manner heretofore common and well understood.

It will of course be understood that any one of a number of well-known devices for giving variable motion to the shaft H' may be employed in place of the particular one shown.

The bobbin or thread-holder J herein shown is made in circular form and located within the central open space of the ring-shaped shuttle. Said bobbin consists of two convex plates, j, j', united by a tubular connecting-piece, j'', forming the barrel upon which the thread is wound. The said bobbin may be held in place within the shuttle in any manner adapted for allowing the free passage of the bobbin-thread outwardly through the marginal slot of the bobbin in the revolution of the shuttle. In the particular construction shown the shuttle is provided with an annular ledge or shoulder, g⁵, against which the inwardly-turned free edge of the plate j' of the bobbin rests, said plate j' being held in contact with the ledge by means of a projection, g⁴, at one side of the shuttle and a spring-catch, g⁵, at the other side thereof. Said spring-catch allows the bobbin to be readily removed from and inserted in the shuttle. The plate j of the bobbin is made of less diameter than the plate j', thereby affording a free space for the egress of the thread, as clearly shown in Fig. 6.

The inclined notch g of the shuttle, within which the loop of the needle-thread is caught, and by which said loop is carried downwardly and around the bobbin, is extended to a point inside of the inner faces of the ribs f² f², between the grooves f f of the castings F F', so that as the shuttle is turned the thread-loop will pass clear of the said ribs, as clearly shown in Figs. 2, 7, and 11. As the shuttle 100 is being turned or revolved to carry the needle-thread loop around the shuttle the said loop will obviously be confined in the notch g by the edges of the adjacent ribs f² f². To provide means for the escape of the 105 needle-loop from the said notch before the carrier has made a complete revolution, so that the needle-thread loop may be drawn up to complete the stitch before the needle again descends into position for the engagement of the shuttle-hook with the upper 110 thread, the edge of the shuttle is cut away through a space of nearly one-quarter of the circumference of the shuttle, so as to form a curved surface, g⁶, which is free from 115 contact with the shuttle bearing or race. The edge of the shuttle adjacent to the part or surface g⁶ is also desirably made narrower than the body of the shuttle, as shown in Fig. 6, to provide additional space for the free 120 passage of the loop through the notch g as the said loop is drawn upwardly by the needle. The sides of the guide-grooves f may also be 125 cut away, as indicated at f², Figs. 6 and 7; but this is obviously not necessary, inasmuch as the narrowing of the edge of the shuttle will usually afford ample space for the upward 130 passage of the loop. The notches g² are made of such depth as to extend into the cut-away

part g^6 of the shuttle, so that the spur-wheel H will properly engage the shuttle at this point. Inasmuch as the formation of the laterally-curved hook g' necessitates the removal 5 of the metal along the center of the edge of the shuttle, as shown in Fig. 5; one of the recesses, g^2 , is placed near the point of the hook near the side face of the shuttle, in the manner clearly shown in said Fig. 5, the tooth of 10 the drive-wheel H engaging the said recess of course being arranged to correspond in position and size with the said recess. The recess g^2 , which is formed in the depressed surface g^6 adjacent to the hook, is also prefer- 15 ably made narrow, as shown in Fig. 5, to enable a rounded and tapered shape to be given to the shuttle at this point.

In Fig. 8 the shuttle is shown in position when the hook is engaged with the needle- 20 thread and the needle rising. Fig. 9 shows the loop as engaged with the notch g and as being carried around the bobbin. Fig. 10 shows the position of the shuttle at the time of the es- 25 cape of the loop from the hook, the loop being shown in the act of being drawn up to complete the stitch.

In a gang-machine of the character shown, in which the shuttles are placed close together, the drive-wheels H for the several shuttles 30 will be united in a single cylinder provided with parallel rows of cogs or teeth to engage the several shuttles.

Shuttles constructed and actuated in the manner set forth may be advantageously em-

ployed in single-needle machines; but such 35 shuttles are especially adapted for use in gang-machines, for the reason that each shuttle and its supporting and actuating devices occupy a narrow space only, so that a number of shuttles may be placed side by side in po- 40 sition to act in connection with a series of needles placed close together without inter- ferring one with the other. A gang-machine embracing a series of shuttles constructed in the manner herein set forth is therefore herein 45 claimed as part of my invention.

I claim as my invention—

The combination, with a plurality of recip- 50 rocating needles, of a series of circular re- volving hooked shuttles moving in planes par- allel with planes passing through the vertical axes of the needles at right angles to the com- mon axes of the shuttles, circular guides or 55 bearings engaging the margins of said shut- tles, said shuttles having recesses formed in their peripheries, and revolving drive- wheels mounted upon one side of the shuttle and having teeth formed on their peripheries adapted to engage with the recesses in the 60 shuttles whereby the same are driven, substan- tially as described.

In testimony that I claim the foregoing as my invention I affix my signature in presence of two witnesses.

MARSHALL GARDNER.
